CLAIM

The ornamental design for a handheld fabric sweeper, as
shown and described.

DESCRIPTION

FIG. 1 is perspective view of an embodiment of a fabric
sweeper incorporating our new design, viewed from in back
of, above, and from the right side of the fabric sweeper;

FIG. 2 is a right side elevation view thereof showing the
rollers in phantom, with the left side being a mirror image
of the right side;

FIG. 3 is a rear elevation view thereof showing the rollers in
phantom, with the front being a mirror image of the rear;

FIG. 4 is a top plan view thereof; and,

FIG. 5 is a bottom plan view thereof with the rollers shown
in phantom.

Wherein the broken lines form no part of the claimed design.
